UNITED STATES PATENT OFFICE.

HARVEY H. TROXEL, OF ASHLAND, OHIO.

RESILIENT HEEL AND TREAD-INSERT.

1,399,328.

Specification of Letters Patent.

Patented Dec. 6, 1921.

Application filed August 7, 1920. Serial No. 401,846.

To all whom it may concern:

Be it known that I, HARVEY H. TROXEL, a citizen of the United States, residing at Ashland, in the county of Ashland and State 5 of Ohio, have invented certain new and useful Improvements in Resilient Heels and Tread-Inserts, of which the following is a specification.

My invention relates to improvements in 10 resilient heels and tread inserts, the heel being improved through the provision of certain novel coöperating features of construction together with an improved wear resisting tread insert.

15 My invention relates more particularly to an improved wear resisting tread insert particularly designed and adapted for use in the specific form of a nail or a fastener to be inserted in any portion of a shoe heel or sole 20 for the purpose of preventing wear without impairing the resiliency thereof.

The primary object of the invention is to provide a generally improved resilient heel and tread insert of the character indicated 25 which will be exceedingly simple in construction, cheap of manufacture, and efficient in use.

A further and very important object of the invention is the provision of a generally 30 improved fastener or tread insert for shoes comprising relatively fixed and movable shank and head members, said shank member, in the present instance, being in the specific form of a nail adapted to be driven into 35 the tread portion of a shoe heel, or the like, and said head member being in the specific form of a relatively movable head or wear resisting tread member adapted to protect the elastic tread portion and to move inwardly and outwardly with the latter during 40 the walking or tread movements of the wearer.

A further object is the provision of an improved tread insert adapted also to act as a 45 fastener member for the elastic tread portions of a shoe, and comprising telescoping nail and head members, said nail member acting as a stop for limiting the inward and outward movements of the head member in 50 actual service.

With the above mentioned and other ends in view, the invention consists in the novel construction, arrangement, and combination of parts, hereinafter described, illustrated in

some of its embodiments in the accompanying drawings, and particularly pointed out in the appended claims.

Referring to the drawings, forming a part of this specification, Figure 1 is a plan view of the under or face side of a resilient heel 60 of the full heel type embodying improved fastener tread inserts constructed and arranged in accordance with this invention.

Fig. 2, a central longitudinal sectional view taken on line 2—2 of Fig. 1.

Fig. 3, an enlarged detailed view of one of the fastener tread inserts removed, the parts being in their extended positions.

Fig. 4, a view of the same, partly in section, the parts being in their retracted or 70 collapsed position preparatory to driving.

Fig. 5, a view of the same in fully extended position and illustrating in particular the stop members thereof for limiting the outward movement of the tread or head 75 member relative to the relatively fixed or nail member thereof.

Fig. 6, a plan view of the underside or tread portion of a heel of the heel-lift type with a modified form of fastener tread in- 80

Fig. 7, an enlarged cross-sectional view of the same, taken on line 7—7 of Fig. 6.

Similar numerals of reference designate like parts throughout all the figures of the 85 drawings.

The improved heel may be either of the full heel type, as shown in Figs. 1 and 2 of the drawings, or of the heel-lift type, as shown in Figs. 6 and 7 of the drawings.

The improved heel or heel lift comprises a suitable resilient body 1, preferably of suitable homogeneous molded rubber or resilient composition, said resilient heel being preferably provided with similarly shaped 90 tread and recess portions 1^a and 1^b, respectively. The tread portion 1^a, may be of any suitable form or configuration and is preferably arranged slightly to one side of the rear central portion of the heel, and the recess portion 1^b, is adapted to form an air cushioning chamber 1^c, in the top portion of the resilient heel body above the tread portion 1^a, and to coöperate with the latter in giving the requisite cushioning effect.

The recess and chamber portions 1^b and 1^c, may be omitted in a resilient heel of the heel-lift type, as shown in Figs. 6 and 7 of the

drawings, and in either instance the heel or heel lift may be secured to the heel portion of the shoe sole 2, or to the heel lift 2^a, as shown in Fig. 7 of the drawings, through 5 the medium of suitable nails or attaching elements in the usual and well known manner.

The improved tread insert comprises relatively fixed and movable members 3 and 4, 10 respectively, said relatively fixed member 3, in the present instance, comprising a shank member 3, in the specific form of a nail, provided with a head 3^a, to form a stop for the relatively movable members. The relatively 15 movable tread member 4, in the present instance, is in the specific form of a tread head provided with a tubular shank 4^a, slidably receiving the head portion 3^a of the nail or shank member 3, said tubular member 4^a, 20 terminating in inturned stop flanges 4^b, adapted to engage with the stop head 3^a, of the fixed member or nail in limiting the outward movement of the wear resisting head or tread member 4.

25 When it is desired to drive the tread insert into the resilient tread portion to be protected, the telescoping members 3 and 4, may be initially retracted to the position indicated in Fig. 4 of the drawings, so that 30 the head 3^a will come into engagement with the under side of the tread head 4, and the parts may then be driven in a manner similar to an ordinary nail or fastener. It will be obvious that the resiliency of the heel or 35 adjacent tread portion will cause the final blows imparted to the head 4, to drive the head 3^a, of the nail or shank 3, slightly beyond or out of the plane of the tread surface of the heel, as indicated most clearly in 40 Fig. 2 of the drawings, the resiliency of the adjacent portion returning the tread head portion 4 to the normal plane of the heel, and it will thus be obvious that in the ordinary use of the heel the initial tread movement 45 of the heel will cause the tread head to yield and move downwardly therewith until stopped by the engagement of the inner side of the head 4, with the head 3^a, of the shank or nail member 3, acting as a stop member 50 therefor.

The wear resisting tread or head member 4 may be of any suitable form or configuration, as for example, in the form of an elongated head or plate, as shown in Figs. 6 and 55 7 of the drawings, and, if it is desired, to also limit the outward movement of the tread head 4 as in an ordinary fastening element, the tubular shank 4^a may be shortened somewhat so that the stop flanges 4^b will 60 engage with the head 3^a in the normal position of the tread insert 4, as indicated most clearly in Fig. 7 of the drawings.

Any suitable number of tread inserts may 65 be used, as for example, a series or plurality of suitably spaced tread inserts, as shown in

Fig. 1 of the drawings, or where an elongated head or plate is used a single insert may be used, as shown in Figs. 6 and 7 of the drawings.

While I have shown my improved wear 70 resisting tread insert in connection with a resilient shoe heel, it will be obvious and should be understood that the basic principles thereof may be readily adapted for use in other places, as for example, the tread or 75 tip portions of a resilient shoe sole, as well as in other places where it is desired to preserve the resiliency of the material and at the same time protect the same from wear.

Having thus described some of the embodiments of my invention, without having attempted to set forth all the forms in which it may be made, or all the modes of its use, what I claim and desire to secure by Letters Patent, is,—

1. A resilient heel having a fastener, and a relatively movable fastener driving head constituting a tread insert for the heel.

2. A fastener and tread insert, comprising relatively fixed and movable shank and head 90 members, said head member constituting means for driving said shank member and forming a tread insert.

3. A tread insert, comprising relatively fixed and movable shank and tread head 95 members, one of said members forming a stop for limiting the inward and outward movement of the other.

4. A resilient heel, and a fastener tread insert in said resilient heel comprising relatively fixed and movable nail and nail driving members limiting the movement of said resilient heel.

5. A heel having an elastic tread, and a fastener tread insert in said elastic tread 105 comprising relatively fixed and movable shank and driving members, respectively, for limiting the movement of said tread insert and resilient tread.

6. A resilient heel having similarly shaped 110 and located tread and chambered portions at one edge thereof, said tread portion being provided with a fastener having a relatively hard fastener driving tread insert having a limited movement toward and from said 115 chambered portion with the tread movements of said tread portion.

7. A fastener tread insert for shoes, comprising telescoping nail and head members, said nail member forming a stop for limiting the inward and outward movements of the head member, and said head member forming a driving head and affording a wear resisting tread adapted to move inwardly and outwardly during the tread movements 125 of the wearer.

8. In a shoe, a resilient heel, and a tread insert comprising relatively fixed and movable nail and driving head elements, said movable driving head element forming a 130

wear resisting tread and having a guide shank movable relative to and stopped by said fixed element.

9. A fastener tread insert for shoes, comprising telescoping nail and nail driving head members, said nail member having a stop for limiting the inward and outward movements of the head member, and said

head member having a tubular shank surrounding said nail and stop, and when normally seated forming a wear resisting tread movable inwardly and outwardly during the tread movements of the wearer. 10

In testimony whereof I have affixed my signature.

HARVEY H. TROXEL.
